DESIGN FOR A CAPE.

" Design No. **6,632**, dated May 6, 1873

UNITED STATES PATENT OFFICE.

MARTIN LANDENBERGER, JR., OF PHILADELPHIA, PENNSYLVANIA.

DESIGN FOR A CAPE.

Specification forming part of Design No. **6,632**, dated May 6, 1873; application filed April 8, 1873.

To all whom it may concern:

Be it known that I, MARTIN LANDENBERGER, Jr., of Philadelphia, Pennsylvania, have invented a Design for a Garment, of which the following is a specification:

My design for a circular garment or cloak is clearly represented by the figure in the accompanying drawing. It has a hood, A, formed with lapels *a a* and *b b*, edged with a deep fringe, *d*, similar to that extending around the semicircular outline of the garment, and is also ornamented by tassels *e* and *f*. The garment is, in the present instance,

slashed or split at *g*, but this is immaterial and forms no part of the design.

Irrespective of the colors employed, I claim—

The design for a garment, substantially as described, and as represented in and by the accompanying drawing.

In testimony whereof I have signed my name to this specification in the presence of two subscribing witnesses.

MARTIN LANDENBERGER, JR.

Witnesses:

J. J. BUCHEY,
JNO. JAY WARD.
